UNITED STATES PATENT OFFICE.

SAMUEL GOODKIND, OF NEW YORK, N. Y.

CARTON.

1,138,469.

Specification of Letters Patent. Patented May 4, 1915.

Application filed February 25, 1915. Serial No. 10,468.

To all whom it may concern:

Be it known that I, SAMUEL GOODKIND, a citizen of the United States, and a resident of the city of New York, borough of Manhattan, in the county and State of New York, have invented a new and Improved Carton, of which the following is a full, clear, and exact description.

My invention has for its object to provide 10 a carton which may be used for keeping cereals clean and free from dust, the carton being so constructed that when it is opened, one of its parts will serve as a spout and another of its parts will serve as a means to 15 retard the flow of the cereal from the carton to the spout.

Additional objects of the invention will appear in the following specification in which the preferred form of my invention is 20 disclosed.

In the drawings similar reference characters refer to similar parts in all the views in which—

Figure 1 is a perspective view showing the 25 carton with its parts in position to permit the user to pour the contents from the carton; Fig. 2 is a fragmentary view showing the position of the spout after it has been raised; Fig. 3 is a fragmentary perspective 30 view showing how the spout and the tongue appear when the tongue has been disposed between the spout and the wings which are connected therewith; Fig. 4 is a sectional view on the line 4—4 of Fig. 3; and Fig. 5 is a sectional view on the line 5—5 of Fig. 3; Fig. 6 is a face view showing the blank 35 which is used in the construction of the carton.

By referring to the drawings it will be 40 seen that a blank 10 is provided, there being longitudinal creases 11, 12, 13 and 14 along the blank, dividing the blank into portions 15, 16, 17, 18 and 19, a flap 20 extending from the end portion 15 as shown in Fig. 6 of the 45 drawings. Extending from the middle portion 17 of the blank there is a spout 21 having a cutaway portion 22 to assist in directing the flow of the cereal or other goods contained in the carton over the edge of the 50 spout adjacent its center, the said spout 21 being integral with the blank as illustrated in Fig. 6 of the drawings, and being also integral with the wings 23 which are disposed at the sides of the spout 21, the said wings 55 being also integral with the portions 16 and 18 of the blank. There are obliquely dis-

posed creases 24 in the wings 23, the said creases extending from the creases 12 and 13 where they intersect with the crease 25 which separates the spout 21 from the middle portion 17 of the blank 10. This crease 25 is extended and serves to separate the wings 23 from the portions 16 and 18 of the blank. I prefer to cut the wings 23 as shown in Fig. 6 of the drawings with edges 26 forming a continuation of the outer edges 27 of the spout and with edges 28 which are substantially in alinement with the creases 11 and 14. The wings 23 are cut from the edges 28 to the creases 24, the edges 29 with the edges 28 forming an obtuse angle, the wings being also cut from the edges 26 to the creases 24; as at 30, the edge 30 forming with the edges 26 obtuse angles, the edge 30 also forming with the edges 29 obtuse angles. Extending 70 from the portion 19 of the blank there is a tongue 31 with a bent end 32 and extending from the portion 15 of the blank 10 there is a partition 33 having a cutaway portion 34 through which the cereal may flow from the 80 carton to the spout, when the parts of the blank are folded and are secured together as shown in Figs. 1, 2, and 3 of the drawings. Extending from the end 35 of the blank 10 there is a flap 36 which projects from the 85 middle portion 17 of the blank 10. There is also a flap 37 which extends from the portion 16 of the blank 10 at the blank's end 35, and from the portion 18 of the blank there is a flap 38. In addition, there is a flap 39 which 90 extends from the portion 19 of the blank.

When the blank 10 is folded at its creases 11, 12, 13 and 14, the portions 16, 17, 18 and 19 form the sides of the carton and the portion 15 of the blank is disposed below the 95 portion 19, and is secured thereto, the flap 20 being secured to the portion 18 of the blank which forms a side of the carton. The partition 33 is then bent inwardly so that it is disposed as best illustrated in 100 Fig. 1 of the drawings, the opening 34 in the partition permitting the cereal to flow from the carton to the spout 21. When the wings 23 are bent at their creases 24 and also at their creases along the lines where they are 105 united with the spout 21 and the portions 16 and 18 of the blank, it is possible to bend the wings 23 inward at their portions 40 which will draw inwardly the portions 41 of the wings 23 and with the said portions 41, the spout 21. When this is done, the tongue 31 may be inserted between the spout

21 and the portions 41 of the wings 23 and the tongue and the spout may be pressed inwardly until they assume the positions illustrated in Fig. 3 of the drawings when the 5 carton will be securely closed to prevent the dust and dirt from reaching the contents of the carton.

Having thus described my invention I claim as new and desire to secure by Letters 10 Patent:

1. In an article of the class described, a carton having four sides and an end, a spout at the end forming a continuation of one side, wings at the side of the spout connecting the spout with the sides of the carton adjacent the carton's side from which the spout extends, there being creases in the wings, and a tongue on the carton's side opposite the first mentioned carton's side for 15 disposal between the spout and the wings for closing the carton.

2. In an article of the class described, a carton having four sides and an end, a spout at the end forming a continuation of one side, wings at the side of the spout connecting the spout with the sides of the carton adjacent the carton's side from which the spout extends, there being creases in the wings, and a tongue and a partition extending 20 from the carton's side opposite the first mentioned carton's side, the partition being disposed within the tongue and having an opening adjacent the carton's side having the spout to permit a limited flow of the contents of the carton to the spout, the tongue being provided for disposal between the spout and the wings for closing the carton.

3. In an article of the class described, a carton having four sides and an end, a spout 40 at the end integral with and forming a continuation of one of the sides, wings at the sides of the spout, the wings being integral with the spout and with the carton's side adjacent the carton's side having the spout, there being diagonal creases in the wings 45

and a tongue integral with and extending from the carton's side opposite the first carton's side for disposal between the spout and the wings.

4. In an article of the class described, a blank having four longitudinal creases separating five portions, the blank being folded at the creases with one of the end portions disposed over the other end portion and secured thereto to form a carton having four sides, an extension at one end of the middle portion of the blank forming a spout, wings integral with the sides of the spout and with the portions of the blank adjacent the said middle portion, there being oblique creases 60 in the wings, and a tongue extending from one of the end portions of the blank for disposal between the spout and the wings for the purpose specified.

5. In an article of the class described, a blank having four longitudinal creases separating five portions, the blank being folded at the creases with one of the end portions disposed over the other end portion and secured thereto to form a carton having four sides, an extension at one end of the middle portion of the blank forming a spout, wings integral with the sides of the spout and with the portions of the blank adjacent the said middle portion, there being oblique creases 75 in the wings, a partition extending from the inner end portion of the blank for disposal across an end of the carton to retard the flow of the contents, and a tongue extending from the outer end portion of the blank for 80 disposal between the spout and the wings for the purpose specified.

In testimony whereof I have signed my name to this specification in the presence of the two subscribing witnesses.

SAM'L GOODKIND.
